4 Sheets-Sheet 1

Fig. 1.

This diagram illustrates a complex vacuum tube circuit, likely a radio receiver and amplifier system. The circuit is organized into several functional blocks:

- Power Source:** A battery is connected to terminal 10, with the negative terminal at 13' and the positive terminal at 10.
- Antenna:** The antenna is connected to terminal 13 and ground.
- Detector and Amplifier Stages:** The circuit includes multiple stages of detection and amplification. Key components include:
  - A grid leak detector stage with tubes 13' and 13.
  - A power supply section with tubes 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164.
  - An **AMPLIFIER** stage.
  - A speaker output terminal 108.
- Control and Modulation:** The circuit includes a modulator section with tubes 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164.
- Local Oscillator:** A local oscillator section with tubes 14, 14', 145, 146, 147, 148, 149, 150, 151, 152, 153, 154, 155, 156, 157, 158, 159, 160, 161, 162, 163, 164.

WEB REGISTERING MECHANISM

Hermann Kott, East Orange, N. J., assignor, by
mesne assignments, to Speedy Gravure Corpora-
tion, Hoboken, N. J., a corporation of New
York

Application September 6, 1939, Serial No. 293,527

20 Claims. (Cl. 177—311)

The present invention relates to web register mechanisms for printing presses and embodies, more particularly, an improved registration mechanism by means of which proper control of the web may be facilitated where a sequence of operations are to be performed upon the web. More particularly, the invention is concerned with mechanisms for indicating or controlling the movement of the web with respect to two or more printing cylinders so that effective registration of the web with each successive printing cylinder may be accomplished.

In the web printing art, where two or more impressions are to be applied to a continuous web of paper or the like, and particularly where the impressions are to be properly related to form a common image, such, for example, as in multi-color printing, it is extremely important that all of the impressions forming the image be accurately applied to the web so that each will be in register. For example, where a multicolor image is to be formed by superimposing one color upon another, if the colors are not exactly in register, the edges of regions in which the various tones or colors occur will be fringed or haloed by reason of the fact that the colors are incorrectly combined at these edges. In multi-color printing, therefore, it becomes particularly important to effect accurate registration of the various component colors and numerous attempts have been made to solve this problem.

I have found that the most effective way of accomplishing this result, particularly where the web travel is at speeds of 500 to 1000 feet per minute or even more, is to determine and control the operation electrically. In my copending application Serial No. 211,365, filed June 2, 1938, I have described a mechanism by means of which web registration may be accurately indicated. The present invention embodies important improvements which I have found to overcome certain inherent operating difficulties that are met with in printing operations.

An object of this invention, accordingly, is to provide an improved web register control or indicating mechanism by means of which accurate indication or control of the condition of registration may be had under all conditions of operation, particularly where the press operating speeds are high. It is to be recalled that, in modern high speed printing operations, the indicating or controlling mechanism must be fully responsive to changes in frequency of occurrence of a printed impression on a web at any particular stage in the printing operation, where

the web is traveling at speeds of, say, 1000 feet a minute. The frequency of such occurrence at each printing unit may thus be five per second and, in the device shown and described in my 5 co-pending application above referred to, the mechanism utilizes spots that are printed on the web by the printing cylinders that print the respective colors. Photoelectric cells are utilized to pick up these spots (being responsive to changes in light intensity caused by such spots) and the resulting change in the photoelectric cell circuit is used in timed relation with the rotation of the respective cylinders to indicate whether the spot occurrence at the respective cylinders is in proper timed relation to the cylinders so that the successive printings may be properly registered with the other impressions.

The first object of the invention, as stated above, therefore, contemplates the provision of 20 an improved electric circuit which is fully responsive to the high frequencies of spot occurrence on the web under all conditions of operation and, in the embodiment of the invention shown and described herein, the object is 25 achieved by utilizing the cathode ray tube utilized in the mechanism described in my aforesaid copending application with improved control mechanism and circuits so that the cathode ray beam may be modulated by impulses resulting from improper conditions of web registration.

A further object of the invention is to provide an improved mechanism of the above character whereby carrier frequencies are produced 35 that, under improper conditions of registration, are modulated to cause a desired indicating or controlling operation to be effected.

A further object of the invention is to provide 40 an improved photoelectric cell circuit for the cathode ray tube above referred to by means of which a normal condition of the circuit may be preserved which results in more dependable and accurate operation of the mechanism. More particularly, this aspect of the invention is 45 achieved by utilizing a double light beam system, the individual light beams of which are 180° out of phase, by means of which the aforesaid double beam system may be utilized with the photoelectric cell to produce carrier frequencies that are modulated by the spot occurrence on the web, so that if out of register, current impulses supplied to an amplifying circuit 50 may give a desired indication.

Yet another object of the invention is to provide 55 a mechanism, utilizing the above double

beam system, by means of which the occurrence of the spot on the web will always receive the light beam, thus avoiding the occurrence of the spot during the interval of time when the light beam is interrupted.

A further object of the invention resides in the provision of an improved method and apparatus by means of which external disturbances that are frequently occasioned on portions of the web may be prevented from producing false indications of lack of registry, when, actually, proper registration exists at each of the printing units. This object is achieved by utilizing one of the colors or printed impressions as a key to counteract the effect of the impulses or modulations impressed upon the cathode ray tube by the spot occurrence of other colors as long as the spot occurrences are in register, but, when any of the spot occurrences is out of register, the key color or spot will fail to counteract its modulation of the cathode ray beam.

A further object of the invention is to provide an improved control element by means of which the rotation of the printing cylinder may be effectively synchronized with the modulations of the cathode ray beams occasioned by the photoelectric cells of the respective colors. More particularly, this object is achieved by an improved time segment mechanism actuated in synchronism with the drive for the printing cylinder and is so constructed that a dead segment is provided over which a contact timing arm moves, the segment being of such formation that at least one modulating cycle will always be present in the cathode ray beam control circuit during the time that the arm engages the dead segment.

A further object of the invention is to provide an improved driving mechanism for the synchronizing control switch of the cathode ray beam control circuit by means of which the switch will always be in proper synchronism with the rotating cylinder.

A further object of the invention is to provide, in a drive mechanism for the above mentioned control switch, an improved adjusting mechanism by means of which the control switch may be set effectively in the proper zero position.

A further object of the invention is to provide an improved mechanism, in combination with the photoelectric light beam control mechanism, by means of which the light beam control mechanism may be effectively adjusted during operation.

Yet another object of the invention is to provide an improved web adjusting mechanism that is automatically responsive to conditions of lack of registry of the web to move the web immediately into proper register so that, within permissible tolerances, the web will always be in proper registration.

Further objects of the invention will be apparent as it is described in greater detail in connection with the accompanying drawings, wherein:

Figure 1 is a diagrammatic illustration of the electrical circuits and control mechanism, in which the present invention is embodied;

Figure 2 is a view in vertical section, taken on the section line 2—2 of Figure 3 and looking in the direction of the arrows, illustrating a light beam control mechanism constructed in accordance with the present invention;

Figure 3 is a view of the device in Figure 2 taken on the section line 3—3 and looking in the direction of the arrows;

Figure 8 is a schematic illustration of an automatic web tension controlling mechanism constructed in accordance with the present invention;

Figure 9 is a schematic illustration of a modified means for utilizing a key color negativating the effect on the cathode ray of impulses due to proper register.

Figure 10 is a further modification of the circuits shown in Figure 9;

Figure 11 is a schematic illustration of the advantage of utilizing two frequencies during the time of spot occurrence under the path of the light beam; and

Figure 12 is a schematic illustration of the way in which the carrier frequencies are modulated by the spot occurrence during proper registry.

Referring particularly to Figure 1, the electrical circuits of the indicating and control mechanism of the present invention will be described. In order, however, to appreciate, in a general way, the mechanism in connection with which the present invention may be utilized, it is to be noted that one printing unit of a multi-unit printing press is illustrated schematically in Figure 1 as including a printing cylinder 100 having a drive shaft 101 and an impression roller 102. The paper or other web 103 is received from a previous printing unit or units and is carried along over suitable guide rollers 104 and tension adjusting rollers 105. Each printing cylinder, in each rotation thereof, applies a spot 106 to the web in separate and distinct transversely disposed paths, and a suitable spot responsive mechanism is provided for each path so that determination of the condition of register of each of the cylinders may be accomplished. The spot-responsive mechanism will be described herein-after, and it need only be added that the several printing cylinders and other driven mechanism of the press is driven from a drive shaft 107 through suitable gears 108, an electric motor 109 being furnished to drive the drive shaft.

A transformer 11 is shown as providing a source of power from three secondary coils 12, 13 and 14. These coils supply power to tube circuits in a manner now to be described.

The secondary coil 12 is connected to a wire 15 and to a wire 16 connected to the filament 17 of a two-element tube 18. The filament circuit is completed by a wire 19 which is connected to an auxiliary secondary winding 12' in a known manner.

The plate 20 of the tube 18 is connected, by means of a wire 21, to a condenser 22 that is connected to the wire 15 by means of a connecting wire 23, and the wire 15 is grounded at 24.

In effecting accurate indication and control of the web registration, a cathode ray beam is utilized, the beam being provided by a cathode ray tube 154 having a cathode 26, a control elec-

trode 27, a focusing anode 28, an accelerating anode 29, beam travel plates 30 and 30', and beam deflecting plates 31 and 31'. This cathode ray tube is of standard form and need not be further described herein.

Current is supplied to the cathode filament by means of a battery or other source of power 32 and power circuit 33. The cathode is connected, by means of a wire 34, to a resistance 35 at the point 36. Resistance 35 is connected to the wire 15 by means of a connecting wire 37 and the cathode ray tube is thus supplied by power from the power source 11. The control electrode 27 is connected to the resistance 35 through a wire 38 and contact member 39, the contact member 39 being connected to the resistance 35 at a point more negative than the point 36, also in accordance with known practice. The focusing anode 28 is connected to the resistance 35 by a wire 40 and contact member 41, the engagement of the contact member 41 with the resistance 35 being at a point more positive than the point 36. The accelerating anode 29 is connected to the wire 15 by means of a wire 42. The foregoing cathode ray connections and circuits form no part of the present invention.

In order to cause the cathode ray beam to travel periodically back and forth across the fluorescent screen, the plates 30 and 30' are connected in a circuit including a wire 43 which receives power from a time switch indicated generally at 44 in a manner now to be described. The circuit of plates 30 and 30' is completed by a ground connection 45.

The time switch mechanism is illustrated in Figures 6 and 7 and consists of an insulating disc 46 carried by a sleeve 47. The disc is provided with a series of spaced contacts 48 between which resistance coils are connected to form, in effect, continuous coils 49 and 50 (Figure 1). Adjacent ends of coils 49 and 50 are connected to a central segment 51 which is grounded at 52 and a contact arm 53 is mounted upon a shaft 54 and driven by gearing 55 which in turn is driven from the shaft 107 that drives the printing cylinders.

As will be seen in Figure 1, the arm 53 is connected to the wire 43. This may be accomplished by means of a contact ring 56 carried upon an insulating plate 57 mounted upon a cover plate 58. The arm 53 may have contacts 59 and 60 for engaging the contacts 48 and ring 56, respectively, the contacts being mounted suitably so that there is no thrust on the end of the arm 53.

Adjustment of the zero position of the plate 46 may be effected by means of an electric motor 61, gear reduction 62, drive shaft 63, and worm 64 engaging a worm wheel 65 on sleeve 47.

The coils 49 and 50 of the time switch mechanism are supplied with power from the transformer secondary coil 13 by means of a power circuit now to be described. A rectifier 66 has its plates connected to the secondary 13 by means of wire 67, the filament 68 is energized by an auxiliary secondary coil 13' and the mid-terminal 69 is connected to wire 70 which is connected to the one end of resistance coil 50 through a choke 71 and variable resistance 72. Condensers 73 are connected across the choke 71 and the negative wire 74 which is connected to the mid-point of the secondary coil 13 by means of contact 75. A voltage regulator 76 and condenser 77 are connected across the wires

18 and 14 and the wire 74 is connected to the free end of the resistance coil 49.

The foregoing connections thus complete the power circuit for the time switch mechanism and, as the contact arm 53 rotates, the power in the wire 43 varies from a positive to a negative value periodically. This causes the polarities of the plates 30 and 30' to be reversed to repel and attract, alternately, the cathode ray beam and cause it to travel in the desired fashion.

In order that the cathode ray beam may be modulated by the synchronism of the frequency of spot occurrence with the corresponding point on the respective printing cylinders, the spot responsive mechanism will now be described.

Positioned properly with respect to the web so that it may be affected by the variations of light intensity due to the existence of the spot, is an optical system illustrated in Figures 2, 3, 4 and 5, as well as schematically in Figure 1. This system includes a source of light 110 with a lens system 111 by means of which a light beam is focused directly from the source of light 110 onto the web 103 in the path of travel of the spot 106. If the spot is in the position illustrated in Figures 2 and 4, it will not reflect any light back against the mirrored surfaces 112 and 113 to be reflected upon the photoelectric cell 114. If, however, the spot 106 is not at the point indicated, the web 103 will reflect the light in the manner just described, and cause a variation in the energization of the photoelectric cell 114.

A second optical system 115 is also provided to direct a second light beam directly upon the photoelectric cell 114, as illustrated in Figure 2. The action of this light beam 115 is controlled by means of a prism 116 carried in a sleeve 117 having an aperture 118 through which the light beam passes in its travel to the photoelectric cell, as indicated by the arrow in Figure 2. The sleeve 117 is provided with a gear 119 with which a pinion 120 engages, the pinion being carried upon a shaft 121 that may be driven by a small electric motor 122 for the purpose of adjusting the direction of the beam 115, so that it may subject the photoelectric cell 114 to the desired light intensity.

The beams 111 and 115 are interrupted by means of a disc 123 driven by a synchronous motor 124 and provided with apertures 125. The spacing of the apertures and of the respective light beams 111 and 115 is such that, when an aperture is in register with one light beam to permit it to travel on its desired course, the disc is in register with the other light beam to obstruct it. As the aperture moves out of register with one light beam, another aperture moves in register with the other light beam. The apertures 125 and the locations of the beams 111 and 115 is such that the apertures are 180° out of phase, thus producing two carrier waves 111' and 115' (Figure 12), the result of which is to produce a direct current that is supplied to an amplifier circuit 126, amplifier 127, and wire 128, that is connected to the plate 31. The plate 31' is connected to the ground 45 by means of a wire 45'.

The amplifier 127 is a capacity resistance coupled amplifier of known construction, that includes a condenser that will not pass the aforesaid direct current. However, when the spot occurs under the beam 111, the beam is darkened and the resulting current from the photocell 114 is reduced, producing a wave 111' (Figure 12). The result of the two carrier waves is to produce

a pulsating current that will pass the amplifier 127 and be impressed across the cathode ray plates 31, 31'. Thus, when the spot is in register, one of the waves (115') as controlled by the other wave (111²) causes the cathode ray to be deflected.

In operation the spot size and the speed of the disc 123 and number of apertures 125 is preferably such that, while the spot 106 is in line with the light beam of the optical system 111 (hereinafter referred to as light beam 111) at least two apertures will be successively aligned with the light beam 111. This is illustrated in Figure 11 wherein the beam and spot are shown greatly enlarged and in proper time phase with frequency or wave form 111¹. Thus, with imperfect synchronism of the apertures 125 with the spot 106 there will always result a frequency and prevent no response that would occur if the spot were of such size that, during its alignment with the axis of the beam 111, the disc 123 obstructed the beam by the failure of an aperture to appear while the spot was so positioned.

It will be observed that the greater the number of cycles occurring during the time of spot occurrence, the more accurate will be the indication. For example, in Figure 11, the half cycle 111³ might be lost if the beam were obstructed by the disc during the occurrence of the corresponding portion of the spot under the beam path if the mechanism were in imperfect synchronism. However, by providing a greater multiple of cycles, this lack of sensitivity is correspondingly reduced.

It will be apparent, however, that if the synchronism of the disc 123 with the spot 106 is accurately controlled, only a single cycle is needed for each spot occurrence.

If, therefore, the time switch 44 is adjusted to a zero position in which the contact arm 53 engages the mid-terminal 51, at the time of the impulse from the photoelectric cell 114, by reason of the light beam 115 falling upon it, the cathode ray beam will be deflected at the mid-point of its travel between the plates 30 and 30', as illustrated in Figure 1. If the spot 106 is not in register, the photoelectric cell 114 will be energized either in advance or following the point at which the beam reaches the central position in its travel between the plates 30 and 30' and the cathode ray beam would thus be deflected either before or after it reaches the central point, thus visually indicating the lack of registration both in degree and time.

A further source of power for the cathode ray circuit is provided by the secondary winding 14 and tube 78 to center the path of the beam between plates 31 and 31'. The plate of the tube is connected to the secondary by means of the wire 79 and the filament is energized by an auxiliary secondary 14' and circuit 80, in the known fashion. A resistance 81 is connected across the secondary 14 and tube 78 by means of a wire 82 connected to the tube filament and a wire 83 connected to the secondary 14. A resistance 84 is connected between the wires 82 and 83 and at its mid-point is grounded at 85. A condenser 86 is also connected across the wires 82 and 83. A variable contact 87 is connected by a wire 88 to a resistance 89 and the wire 128, and the wire 88 is grounded at 90 through a condenser 91.

Mechanical variations in printing operations, such as, for example, backlash or hunting of the rolls or the use of different sizes of feed rolls and printing cylinders sometimes cause, or apparent-

ly cause, false indications of the condition of register of the printed material on the web. In order that these mechanical variations in the printing operation may not produce false indications 5 of the condition of register of the web, one of the printed impressions (that is, the spot printed at the time the impression is made) is used as a key color to block out indications provided by the cathode ray beam when the 10 printing units are in the proper condition of register. For example, inasmuch as the black impression is generally used as the key impression in printing, I will describe this aspect of the invention in connection with the use of the black 15 as the key color. To accomplish the intended result, I utilize the impulse derived from the spot corresponding to the black color (hereinafter referred to as the black spot) to nullify the effect produced upon the cathode ray beam by the other spots when the condition of proper registration is secured. To accomplish this, the control electrode 27 is subjected to a negative voltage at the proper time by the black spot.

Referring again to Figure 1, wire 38 includes 25 a resistance 92 across which wires 93 and 94 are connected. Wire 94 is connected to the primary of a transformer 95 and also to the mid-point of its secondary winding. The secondary winding of transformer 95 is connected to a two-way rectifier 96, the central terminal of which is connected to wire 93. Wire 94 is also grounded through a condenser as indicated at 97 and the primary winding of transformer 95 is connected to the photoelectric cell 114' for the black spot 30 through an amplifier 98 by means of a wire 99. By means of the foregoing circuit, the impulse occasioned by the black spot is used to impress 35 a negative voltage upon the control electrode 27 to nullify the effect of the modulation occasioned 40 by the other spots on the web. It is understood, of course, that the cell 114' is provided with the double beam and rotating disc structure previously described herein. The only modulation of 45 the cathode ray beam, accordingly, occurs when the web is out of register with the cylinder corresponding to the photoelectric cell and cathode ray tube in question. When the web is out of 50 register, then the occurrence of the negative voltage on the control electrode, as a result of the black spot, will not be in synchronism with the modulating current from the photoelectric cell 114 and the cathode ray beam will be deflected accordingly.

Figures 9 and 10 illustrate other means for 55 utilizing one color as the key color to nullify the effect produced by the photoelectric cell when the device is in register. In Figure 9, for example, the plate 31 is shown as being formed of two plates 31a and 31b. The impulse received from the photocell sensitive to the black or other key 60 color spot is applied to the plate 31a, whereas the wire 128 is connected to the plate 31b. In this structure, the impulse from the key color is utilized to deflect the cathode ray beam entirely off of the screen when the impulse occurs from 65 circuit 128. In Figure 10 a further modification is shown in which the cathode ray tube is provided with a series of individual plates 31'a and 31'b, each of which is grounded. Plates 31c and 31d cooperate with the respective plates 31'a and 31'b in the following manner. The key color impulse is impressed upon plate 31d by means of a wire 150, whereas the wire 128 is connected to the plate 31c. In this assembly the beam from 70 the key color, by means of plates 31d and 31'b

neutralize the effect of the color beam supplied through the circuit including wire 128 and plates 31c and 31'a. In order to provide more effective control by the use of the key color, the number of impulses in the key color circuit is preferably twice or some other multiple of the impulses in the circuit 128 for the reason previously explained.

In order that the mechanism may be interlocked with the press control mechanism so that it will be disconnected when the press is not operating, the main press control switch is provided with a link 129 that operates a switch 130 to close a circuit 131 including a battery 132 and a relay coil 133. The relay coil 133 closes a switch contact 134 against a spring 135 to close a circuit including a wire 136 connected to the wire 21 and a wire 137 connected to the negative end of resistance 35. When the press is not operating, the relay contact 134 is open and the resistance 35 is thus disconnected from the power circuit.

In Figures 1 and 8 there is shown a device by means of which control of the register of the web may be accomplished automatically. The printing machine, in accordance with common practice, is provided with a reversible electric motor 151 which is utilized to actuate a web tensioning mechanism of suitable form. One such motor and web tensioning mechanism is provided, of course, for each printing unit, and the details of this mechanism need not be described further herein. It is sufficient to state that the motor is controlled by two circuits 152 and 153, each of which includes mechanism operated by a cathode ray tube 154. Within the cathode ray tube are provided beam obstruction plate 155 and 156 spaced at 157 a distance representing the tolerance to be provided in the degree of register accomplished by the mechanism. As long as the cathode ray beam direction is such that the beam passes between the plates 155 and 156 and through the space 157, the operating mechanism will not function. However, if the register is off in either direction, the beam will be deflected from the space 157 to strike the appropriate plate 155 or 156. Assuming that the beam strikes plate 156, the motor 151 will be operated to correct the off-registry by means of a circuit including a wire 158 connected to an amplifier shown schematically at 159. The amplifier is provided with a circuit 160 within which a relay coil 161 is connected, the relay coil serving to move a movable relay contact 162 into contact with a stationary contact 163 and close the circuit 153 connected to the motor 151. When the beam no longer strikes the obstruction plate 156, the relay coil 161 will be de-energized and the contact 162 opened, thus preventing further operation of the control mechanism.

Wire 152 is provided with connections and devices similar to those described in connection with wire 153, being indicated generally at 164.

I claim:

1. In a device for indicating the movement of a drive means for presenting indicia periodically to a desired location, the combination of an electro-responsive device having a first means to maintain a normal electro-responsive operation and having a second means to vary said operation from normal, means responsive to the occurrence of the indicia at the aforesaid location to supply an electric current to the second means, an electrical resistance, means to apply an electrical potential to opposite ends of the resistance, means

to ground the mid-point of the resistance and the first means, a movable contact element for the resistance, means to connect the movable element electrically to the first means, and means to move the movable element in synchronism with the drive means.

2. In a device for indicating the movement of a drive means for presenting indicia periodically to a desired location, the combination of an electro-responsive device having a first means to maintain a normal electro-responsive operation and having a second means to which an electric current having a periodic frequency is applied to vary said operation from normal, means responsive to the occurrence of the indicia at the aforesaid location to supply an electric current having a periodic frequency to the second means, an electrical resistance having a mid-contact, means to apply an electrical potential to opposite ends of the resistance, a movable contact element for the resistance, means to connect the movable element electrically to the first means, and means to move the movable element in synchronism with the drive means, the mid-contact of the resistance being sufficiently wide so that the movable contact element will be in contact therewith to maintain the electro-responsive operation for a time interval sufficient to cause more than one cycle in the current to the second means.

3. In a device for indicating the movement of a drive means for presenting indicia periodically to a desired location, the combination of an electro-responsive device having a first means to maintain a normal electro-responsive operation and having a second means to vary said operation from normal, means responsive to the occurrence of the indicia at the aforesaid location to supply an electric current to the second means, means to direct a light beam to the said desired location and from the said location to the indicia responsive means, means to direct a second light beam to the indicia responsive means, a rotatable apertured disc positioned to intercept said light beams alternately to cause the indicia-responsive means to generate a pulsating electric current having a frequency, an electrical resistance, means to apply an electrical potential to opposite ends of the resistance, a movable contact element for the resistance, means to connect the movable element electrically to the first means, means to move the movable element in synchronism with the drive means, and a mid-contact in the resistance, the length of the mid-contact and the frequency of the interruption of said light beams being such that more than one cycle is impressed upon the second means while the movable contact element is on the mid-contact.

4. In a device for indicating the movement of a drive means for presenting indicia periodically to a desired location, the combination of an electro-responsive device having a first means to maintain a normal electro-responsive operation and having a second means to vary said operation from normal, means responsive to the occurrence of the indicia at the aforesaid location to supply an electric current to the second means, an electrical resistance, means to apply an electrical potential to opposite ends of the resistance, a movable contact element for the resistance, means to connect the movable element electrically to the first means, means to move the movable element in synchronism with the drive means, and means to adjust the relative position of the

electrical resistance with respect to the drive means.

5. In a device for indicating the movement of a drive means for presenting indicia periodically to a desired location, the combination of an electro-responsive device having a first means to maintain a normal electro-responsive operation and having a second means to vary said operation from normal, means responsive to the occurrence of the indicia at the aforesaid location to supply an electric current to the second means, an electrical resistance having a mid-contact, means to apply an electrical potential to opposite ends of the resistance, a movable contact element for the resistance, means to connect the movable element electrically to the first means, means to move the movable element in synchronism with the drive means, and means to adjust the relative position of the mid-contact and the movable contact element.

6. In a device for indicating the movement of a drive means for presenting indicia periodically to a desired location, the combination of an electro-responsive device having a first means to maintain a normal electro-responsive operation and having a second means to vary said operation from normal, means responsive to the occurrence of the indicia at the aforesaid location to supply an electric current to the second means, an electrical resistance having a mid-contact, means to apply an electrical potential to opposite ends of the resistance, a movable contact element for the resistance, means to connect the movable element electrically to the first means, means to move the movable element in synchronism with the drive means, and means to adjust the position of the mid-contact with respect to the drive means.

7. In a device for indicating the movement of a drive means for presenting indicia periodically to a desired location, the combination of an electro-responsive device having a first means to maintain a normal electro-responsive operation and having a second means to vary said operation from normal, means responsive to the occurrence of the indicia at the aforesaid location to supply an electric current to the second means, an electrical resistance having a mid-contact, means to apply an electrical potential to opposite ends of the resistance, a movable contact element for the resistance, means to connect the movable element electrically to the first means, means to move the movable element in synchronism with the drive means, a rotatable disc upon which the resistance element is mounted, and means to adjust the position of the disc to vary the position of the mid-contact.

8. In a device for indicating the movement of a drive means for presenting key and main indicia periodically to separate respective desired locations, the combination of an electro-responsive device having a first means to maintain a normal electro-responsive operation and having a second means to vary said operation from normal, means responsive to the occurrence of the main indicia at its respective desired location to supply an electric current to the second means opposite in effect to the current supplied in response to the main indicia.

9. In a device for indicating the movement of a drive means for presenting key and main indicia periodically to separate respective desired

locations, the combination of an electro-responsive device having a first means to maintain a normal electro-responsive operation and having a second means to vary said operation from normal, means responsive to the occurrence of the main indicia at its respective desired location to supply a periodically pulsating electric current to the second means, and means responsive to the occurrence of the key indicia at its respective desired location to supply a periodically pulsating electric current to the second means having a greater frequency than the current supplied in response to the main indicia and being opposite in effect thereto.

10. In a device for indicating the movement of a drive means for presenting key and main indicia periodically to separate respective desired locations, the combination of a cathode ray tube having a first pair of electrodes and means to direct a cathode ray beam periodically in a normal path back and forth between said first electrodes and a second pair of electrodes adapted to deflect the beam from its normal path, means responsive to the occurrence of the main indicia at its respective desired location to supply an electric current to the second pair of electrodes to deflect the beam from its normal path, and means responsive to the occurrence of the key indicia at its respective desired location to supply an electric current to the cathode ray tube to counteract the effect of the current supplied in response to the main indicia.

11. In a device for indicating the movement of a drive means for presenting key and main indicia periodically to separate respective desired locations, the combination of a cathode ray tube having a first pair of electrodes and means to direct a cathode ray beam periodically in a normal path back and forth between said first electrodes and a second pair of electrodes adapted to deflect the beam from its normal path, means responsive to the occurrence of the main indicia at its respective desired location to supply a periodically pulsating electric current to the second pair of electrodes to deflect the beam from its normal path, and means responsive to the occurrence of the key indicia at its respective desired location to supply a periodically pulsating electric current to the cathode ray tube having a greater frequency than the current supplied in response to the main indicia to counteract the effect thereof.

12. In a device for controlling the operation of mechanism for presenting an indicia to a desired location periodically including electrical mechanism for varying the time of occurrence of the indicia at the aforesaid location, the combination of means responsive to the occurrence of the indicia at the aforesaid location to generate an electric current, a cathode ray tube, means to apply the current to the tube to deflect the cathode ray beam thereof, a beam obstruction surface in the tube, an amplifier circuit connected to the beam obstruction surface, a relay having contacts connected to the amplifier circuit, and a circuit including the relay contacts and the said electrical mechanism whereby improper indicia occurrence at the aforesaid location is corrected by impingement of the cathode ray beam upon the obstruction surface.

13. In a device for controlling the operation of mechanism for presenting an indicia to a desired location periodically having electrical mechanism for varying the time of occurrence of the indicia at the aforesaid location, the combination of means responsive to the occurrence of the indicia

at the aforesaid location to generate an electric current, a cathode ray tube, means to apply the current to the tube to deflect the cathode ray beam thereof, a beam obstruction surface in the tube, a relay having contacts connected to the beam obstruction surface, and a circuit including the relay contacts and the said electrical mechanism whereby improper indicia occurrence at the aforesaid location is corrected by impingement of the cathode ray beam upon the obstruction surface.

14. In a device for controlling the operation of mechanism for presenting an indicia to a desired location periodically having electrical mechanism for varying the time of occurrence of the indicia at the aforesaid location, the combination of means responsive to the occurrence of the indicia at the aforesaid location to generate an electric current, a cathode ray tube, means to apply the current to the tube to deflect the cathode ray beam thereof, spaced beam obstruction surfaces in the tube positioned so that normal deflection of the cathode ray beam occurs in the space between the surfaces, an amplifier circuit connected to each of the beam obstruction surfaces, a relay having contacts connected to each amplifier circuit, and circuits including the respective relay contacts and the said electrical mechanism, whereby improper indicia occurrence at the aforesaid location is corrected by impingement of the cathode ray beam upon the obstruction surfaces.

15. Web register mechanism for controlling means to supply to a predetermined location pre-conditioned portions of a web bearing indicia thereon, comprising a first means responsive to electrical impulses, an indicia responsive means, a light source, means to direct a beam of light from the source to the predetermined location upon the web, to be reflected from said predetermined location to the indicia responsive means, in the absence of an indicium at said location, means to direct a second light beam to the indicia responsive means, means for alternately interrupting said light beams in timed relation to a predetermined desired occurrence at said location of said indicia and means to supply electrical impulses from the indicia responsive means to the said first means to actuate the said first means in timed relation to the occurrence of indicia at the predetermined location.

16. Web register mechanism for controlling means to supply to a predetermined location pre-conditioned portions of a web bearing indicia thereon, comprising a first means responsive to electrical impulses, an indicia responsive means, a light source, means to direct a beam of light from the source to the predetermined location upon the web, to be reflected from said predetermined location to the indicia responsive means, in the absence of an indicium at said location, means to direct a second light beam to the indicia responsive means, means to interrupt said light beams periodically and alternately in timed relation to said means to supply portions of said web, and means to supply electrical impulses from the indicia responsive means to the first means to actuate the said first means in timed relation to the occurrence of pre-conditioned portions of the web at the predetermined location.

17. Web register mechanism for controlling means to supply to a predetermined location pre-conditioned portions of a web bearing indicia thereon, comprising a first means responsive to electrical impulses, an indicia responsive means,

a light source, means to direct a beam of light from the source to the predetermined location upon the web, to be reflected from said predetermined location to the indicia responsive means, in the absence of an indicium at said location, means to direct a second light beam to the indicia responsive means, means to interrupt said light beams periodically and alternately with a periodicity of the desired occurrence of the pre-conditioned portions of the web at the predetermined location, and means to supply electrical impulses from the indicia responsive means to the said first means to actuate the said first means in timed relation to the occurrence of pre-conditioned portions of the web at the predetermined location.

18. Web register mechanism for controlling means to supply to a predetermined location pre-conditioned portions of a web bearing indicia thereon, comprising a first means responsive to electrical impulses, an indicia responsive means, a light source, means to direct a beam of light from the source to the predetermined location upon the web to be reflected from said predetermined location to the indicia responsive means, in the absence of an indicium at said location, means to direct a second light beam to the indicia responsive means, a disc mounted in the path of said light beams, apertures in the disc formed to obstruct one light beam when the other is unobstructed, means for rotating said disc to cause the first mentioned light beam to be directed onto said web in timed relation to a predetermined desired occurrence of indicia at said location and means to supply electrical impulses from the indicia responsive means to the said first means to actuate the said first means in timed relation to the occurrence of pre-conditioned portions of the web at the predetermined location.

19. Web register mechanism for controlling means to supply to a predetermined location pre-conditioned portions of a web bearing indicia thereon, comprising a first means responsive to electrical impulses, an indicia responsive means, a light source, means to direct a beam of light from the source to the predetermined location upon the web, to be reflected from said predetermined location to the indicia responsive means, in the absence of an indicium at said location, means to direct a second light beam to the indicia responsive means, a disc mounted in the path of said light beams, apertures in the disc formed to obstruct one light beam when the other is unobstructed, means to rotate the disc at a speed such that an aperture in the disc will be in register with the first light beam at the time the pre-conditioned portions of the web are in register therewith when the periodicity of occurrence of the pre-conditioned portions of the web at such point is as desired, and means to supply electrical impulses from the indicia responsive means to the first means to actuate the first means in timed relation to the occurrence of pre-conditioned portions of the web at the predetermined location.

20. Web register mechanism for controlling means to supply to a predetermined location pre-conditioned portions of a web bearing indicia thereon, comprising a first means responsive to electrical impulses, an indicia responsive means, a light source, means to direct a beam of light from the source to the predetermined location upon the web, to be reflected from said predetermined location to the indicia responsive means,

in the absence of an indicium at said location, means to direct a second light beam to the indicia responsive means, a disc mounted in the path of said light beams, apertures in the disc formed to obstruct one light beam when the other is unobstructed, means to rotate the disc at a speed such that an aperture in the disc will be in register with the first light beam at the time the indicia on the web are in register therewith

when the periodicity of occurrence of the indicia on the web at such point is as desired, and means to supply electrical impulses from the indicia responsive means to the first means to actuate the first means in timed relation to the occurrence of preconditioned portions of the web at the predetermined location, said means including a condenser.

HERMANN KOTT.
